UNITED STATES PATENT OFFICE

CHARLES JACOBS, OF CONEY ISLAND, NEW YORK

DESIGN FOR AN AMUSEMENT DEVICE

Application filed March 10, 1931. Serial No. 39,018. Term of patent 7 years.

To all whom it may concern:

Be it known that I, CHARLES JACOBS, a citizen of the United States, residing in Coney Island, in the county of Kings and State of New York, have invented a new, original, and ornamental Design for Amusement Devices, of which the following is a specification, reference being had to the accompanying drawings, forming a part thereof, and of which Figure 1 is a view in side elevation and Fig. 2 is a view in front elevation of an amusement device showing my new design.

I claim:

The ornamental design for an amusement device substantially as shown.

CHARLES JACOBS.
